UNITED STATES PATENT OFFICE.

FRANK S. PARRIGIN, OF MARTIN, TENNESSEE.

SYRINGE.

Application filed January 11, 1924, Serial No. 685,589.

To all whom it may concern:

Be it known that I, FRANK S. PARRIGIN, a citizen of the United States, residing at Martin, in the county of Weakley, State 5 of Tennessee, have invented certain new and useful Improvements in Syringes; and I do hereby declare the following to be a full, clear, and exact description of the invention, such as will enable others skilled in the 10 art to which it appertains to make and use the same.

This invention relates to new and useful improvements in syringes, and particularly to vaginal syringes.

15 One object of the invention is to provide a syringe constructed and arranged to more readily permit the liquid to flow from the cavity, after having performed its cleansing or antisepticizing function.

20 Another object is to provide a device of this character wherein the nozzle is capable of extension to suit the depth of the cavity, without interfering with the shield which is placed against the mouth of the 25 cavity.

A further object is to provide a device of this character wherein the outflowing liquid is carried away from contact with the hands of the user.

30 Other objects and advantages will be apparent from the following description when taken in connection with the accompanying drawing.

In the drawing:

35 Figure 1 is an elevation of a syringe made in accordance with the present invention.

Figure 2 is a longitudinal sectional view through the device.

Figure 3 is an end view of the nozzle.

40 Figure 4 is a transverse sectional view on the line 4-4 of Figure 2.

Figure 5 is a transverse sectional view on the line 5-5 of Figure 2, a part of the shield or guard being removed.

45 Referring particularly to the accompanying drawing, 10 represents a cylindrical body, formed from metal, hard rubber, or the like, and having the opening 11 therethrough. The upper portion of the bore is, 50 however, slightly greater in diameter than the lower portion, as shown at 11'. Fitted in the lower portion of the bore 11 is a soft rubber sleeve or bushing 12, the same having terminal peripheral flanges 13 and 14, respectively. The inner end of the portion 11' of the bore is inclined laterally, as shown

at 15, and the upper end of the bushing 12 is correspondingly inclined, so that its flange 13 may rest within the circular channel or ledge 16. Formed on the side of the body 10 is a laterally and downwardly curved pipe 17, the upper end of which opens into the side of the body at approximately the level of the lower side of the inner end of the bore portion 11'. In the lower end of the lower portion of the bore there is formed a circumferential ledge 18 in which the lower flange 14 of the bushing 12 is seated. To the outer end of the pipe 17 a hose 19 is connected, for carrying off the liquid discharge from the cavity being treated.

The outer face of the upper end of the body 10 is threaded, and threaded onto this portion is the dome-shaped guard or shield plate 20, the same extending downwardly, or rearwardly to a point approximately in the plane of the lower side of the inner end of the bore portion 11'. Formed on the lower end of the body 10, at a point diametrically opposite to that of the pipe 17, is a handle member 21, which is adapted to be grasped by the user to maintain the plate 20 properly seated within the mouth of the cavity being flushed.

Slidably disposed through the bore of the body 10, and through the bushing 12, is the stem 22 of the nozzle 23, the inner end of which is formed for receiving thereon one end of a hose, while the other end is formed with longitudinal corrugations 24. Formed longitudinally through the center of the stem and nozzle is a liquid conduit 25, the outer end terminating within a spherical head 26, and radiating from this end of the conduit are short exit passages 27, the same opening through the face of the head for discharging liquid into the vaginal cavity. The formation of the spherical head 26 results in the neck 28, just inwardly of the head, and at which point the corrugations 24 terminate.

It will be noted that the stem 22 fits tightly within the bore of the bushing 12, while the portion of the stem within the portion 11' of the bore of the body is spaced from the walls of said bore portion, thus providing a circular space between the body and stem to permit the liquid to flow from the cavity into the bore, and finally escape through the pipe 17 to a receptacle not shown.

The stem of the nozzle is capable of be-

ing moved longitudinally through the bushing 12, to cause more or less of the nozzle end to project from the upper end of the body, in accordance with the depth of the cavity being treated.

The incline of the bore and bushing serve to deflect the outflowing liquid laterally into the pipe 17, the bushing 12 effectively preventing escape of any liquid therethrough or therearound, which might come into contact with the hand of the user.

The bushing 12 being of soft rubber, the stem 22 will remain in any of its different slideable positions, as will be readily understood.

There is thus provided a device wherein a liquid may be properly injected into a human cavity, perform its cleansing effect, and flow from the cavity, without danger of any of the liquid escaping onto the exterior of the device, or onto the hands of the user. The guard or shield plate 20 effectively closes the mouth of the cavity, so that the liquid may escape only through the passage provided therefor.

What is claimed is:

In a syringe, the combination with a slid-

able nozzle, of a support for the nozzle comprising a cylindrical body having an occlusion shield on one end and a laterally directed handle on the other end, said body having a central longitudinal bore therethrough, the end portion of said bore adjacent the shield being of greater diameter than the remainder of the bore and resulting in a transverse shoulder which is inclined transversely of the bore, the wall of the outer end of the smaller portion of the bore being formed with a surrounding ledge, a bushing fitted within the smaller portion of the bore and having terminal peripheral flanges seated respectively on the said inclined shoulder and said ledge, and a laterally and longitudinally directed discharge nipple formed on the side of the body and communicating with the inner end of the larger bore portion.

In testimony whereof, I affix my signature in the presence of two witnesses.

FRANK S. PARRIGIN.
